INVENTOR

A. E. PARNALL
Chattanooga, Tenn.

BY

UNITED STATES PATENT OFFICE.

ARCHIE E. PARNALL, OF CHICAGO, ILLINOIS, ASSIGNOR TO FRANK W. WILLIAMS, OF CHICAGO, ILLINOIS.

PHONOGRAPH-REPRODUCER.

1,284,136.

Specification of Letters Patent. Patented Nov. 5, 1918.

Application filed August 21, 1917. Serial No. 187,892.

To all whom it may concern:

Be it known that I, ARCHIE E. PARNALL, a citizen of the United States, and a resident of the city of Chicago, in the county of Cook and State of Illinois, have invented certain new and useful Improvements in Phonograph-Reproducers; and I do hereby declare that the following is a full, clear, and exact description of the same, reference 5 being had to the accompanying drawings, and to the numerals of reference marked thereon, which form a part of this specification.

It has been the practice when mounting 15 diaphragms in phonograph reproducers or sound boxes to first place a diaphragm in a sound box and then secure the inner end of a stylus arm to the diaphragm by means of cement or any other suitable material which 20 is placed around the end of the stylus arm to firmly hold the diaphragm and stylus arm secured to one another. This process has not proven satisfactory for the reason 25 that very often the inner end of the stylus arm is not secured directly in the center of the diaphragm but off center which results in the production of disconcerting sound reproductions.

This invention relates to an improved 30 form of a phonograph reproducer wherein the inner end of the stylus arm is adapted to be securely fastened to the exact center of the diaphragm, by means of a resilient member secured between the diaphragm and the 35 reproducer casing.

It is an object of this invention to produce a phonograph reproducer in which the diaphragm and the stylus arm are formed to insure exact centering of the inner end of 40 the stylus arm with respect to the diaphragm.

It is also an object of the invention to construct a phonograph sound box having a grooved gasket member adapted to hold 45 a centrally apertured diaphragm exactly in the center of the sound box to permit the inner hooked end of a stylus arm to be securely fastened directly in the center of said diaphragm.

50 It is furthermore an object of the invention to construct a phonograph reproducer wherein the diaphragm is held exactly in the center of the reproducer to permit the

inner end of a stylus arm to be secured exactly in the center of the diaphragm. 55

It is an important object of the invention to produce a phonograph reproducer of simple and effective construction wherein the stylus arm is insured of being attached to the center of the diaphragm. 60

Other and further important objects of the invention will be apparent from the disclosures in the drawings and specification.

The invention (in a preferred form) is illustrated in the drawings and hereinafter 65 more fully described.

On the drawings:

Figure 1 is a central vertical section taken through a phonograph reproducer embodying the principles of the invention, with 70 parts shown in elevation.

Fig. 2 is a bottom plan view thereof.

Fig. 3 is an enlarged detail section taken on line 3—3 of Fig. 2, with parts broken away. 75

Fig. 4 is a central vertical section of the reproducer diaphragm and its supporting and centering means.

Fig. 5 is an enlarged fragmentary vertical section taken through the central portion of 80 the diaphragm showing the inner end of the stylus arm partly engaged in the central aperture of said diaphragm.

Fig. 6 is a similar section showing the 85 next step in the operation.

Fig. 7 is a similar view showing the stylus arm secured to the center of the diaphragm.

As shown on the drawings:

The reference numeral 1, designates a phonograph reproducer casing or sound box, 90 provided with an inner rectangular peripheral recess 2. Rigidly formed on the exterior at one side of the sound box are two parallel arms 3, having pivotally mounted therebetween by means of pivot screws 4, a stylus comprising a stylus arm 5, and a reproducing needle holder 6, for removably holding a needle 7, in position. The inner portion of the stylus arm 5, is bent substantially at right angles to the main portion 100 of the arm as denoted by the reference numeral 8. Integrally formed on the end and projecting to one side of the bent stylus portion 8, is a hook or projection 9, having a lower straight edge 10, disposed at right 105 angles to the outer edge of the bent stylus.

portion 8. Integrally formed on the inner edge of the bent stylus portion 8, opposite and a little below the projection 9, is a stop or projection 11, the upper edge 12, of 5 which is straight and disposed at right angles to the inner edge of the bent stylus portion 8, and parallel to the edge 10, of the projection 9.

Removably disposed centrally within the 10 sound box 1, is a diaphragm 13, made of mica or other suitable material and having the outer peripheral margin thereof engaged in a continuous groove 14, formed in the inner peripheral surface of a rectangularly 15 cross-sectioned rubber ring or gasket 15, halfway between the top and bottom surfaces of said gasket. The gasket 15, is adapted to seat within the right angled recess 2, formed in the sound box, thus affording a means for holding the diaphragm 13, positioned exactly in the center of the sound box, and preventing the same from shifting laterally. To hold the gasket and diaphragm in position within the sound box, 20 25 a split flat metal spring ring or retaining washer 16, is sprung into the sound box 1, and seats against the lower surface of the gasket 15.

The diaphragm 13, has an aperture or 30 opening 17, formed exactly in the center thereof, to permit the hook 9, of the stylus arm 5, to be projected therethrough as shown in Fig. 5, before the diaphragm 13, and the gasket 15, are mounted in the sound 35 box. The diaphragm and the pivoted stylus arm are then moved toward one another to the position shown in Fig. 6, to permit the straight edge 10, of the hook projection 9, to seat against the top or inner surface of said 40 diaphragm and the straight edge 12, of the stop projection 11, to contact the lower or outer surface of the diaphragm. The gasket and the diaphragm are then positioned in the sound box 1, to insure perfect centering 45 of the diaphragm, and cement or any other suitable material 18, is dropped or disposed around the projection 11, and the bent stylus portion 8, filling the diaphragm aperture 17, after which the diaphragm and the 50 gasket are removed from the sound box, to permit more of the cement 18, to be placed around the hooked stylus projection 9, to unite with the cement already in the aperture 17, thus insuring a good connection between 55 the stylus arm and the diaphragm with the inner end of the stylus arm positioned directly in the center of the diaphragm to permit the sound reproductions to be transmitted through the sound box 60 free from any disconcerting noises.

The diaphragm and its centering gasket

are now replaced in the sound box and the split spring ring 16, is sprung into position against the bottom surface of the gasket to hold the same secured in position. 65

I am aware that numerous details of construction may be varied through a wide range without departing from the principles of this invention, and I therefore do not propose limiting the patent granted otherwise than necessitated by the prior art. 70

I claim as my invention:

1. The combination with an apertured phonograph diaphragm, of a stylus arm, and projections integrally formed on opposite edges and at different distances from the inner end of said stylus arm, one of said projections adapted to project through the apertured diaphragm to engage one surface thereof while the other projection engages 80 the other diaphragm surface. 75

2. The combination with a centrally apertured phonograph diaphragm, of a stylus arm having the inner end bent at substantially right angles to the main portion of 85 said arm, a projection integrally formed at the end and to one side of said bent stylus portion having a straight edge adapted to flatly contact one surface of the diaphragm when said projection is projected through 90 the aperture in said diaphragm, a second projection integrally formed on the opposite edge and at a short distance from the end of said bent stylus portion having a straight edge adapted to flatly contact the other diaphragm surface, and means for securing said projections to the diaphragm insuring proper centering of the diaphragm. 95

3. The combination with an apertured phonograph diaphragm, of a flat stylus arm 100 bent at right angles at its inner end, and flat projections disposed in the same plane and integrally formed on opposite edges of the bent portion of the stylus arm adapted to engage opposite surfaces of said diaphragm. 105

4. The combination with an apertured phonograph diaphragm, of a flat stylus arm, flat projections disposed in the same plane and integrally disposed on opposite edges and at different distances from the inner end 110 of said stylus arm, said projections adapted to engage opposite surfaces of said diaphragm, and means for securing said projections to said diaphragm. 115

In testimony whereof I have hereunto subscribed my name in the presence of two subscribing witnesses.

ARCHIE E. PARNALL.
